UNITED STATES PATENT OFFICE.

PETER O. ROTH, OF NEW YORK, N. Y.

BOILER AND HEATER.

Application filed July 21, 1921. Serial No. 486,409.

To all whom it may concern:

Be it known that I, PETER O. ROTH, a citizen of the United States, and a resident of the city of New York, Middle Village, 5 borough of Queens, in the county of Queens and State of New York, have invented a new and Improved Boiler and Heater, of which the following is a full, clear, and exact description.

10 This invention relates to steam boilers and heaters and has for an object to provide an improved construction over my prior Patent No. 1,272,113, issued July 9, 1918.

Another object of the invention is to provide an improved construction of means 15 for causing the water in the boiler to absorb more of the heat units passing through the flues, the arrangement being adjustable to take care of different conditions of fire, 20 boiler and the like.

A further object of the invention is to provide an improved arrangement of spiral sections for boiler tubes together with means 25 for moving them to an aligned position or a spiral position.

A still further object of the invention is to provide an improved arrangement of baffling or deflecting means for boiler tubes together with a system of operating members 30 at the end of the boiler which may operate any desired series of baffles.

An additional object is to provide not only baffling means for boiler tubes but an improved arrangement of air or steam injection 35 therein which will tend to produce a better combustion and a better draught.

In the accompanying drawings—

Figure 1 is a sectional view through a 40 boiler and furnace showing one embodiment of the invention with certain parts illustrated in elevation.

Figure 2 is an enlarged fragmentary sectional view showing certain details of baffle construction and arrangement for steam injection.

Figure 3 is a detail fragmentary front view of one of the baffle supporting elements.

Figure 4 is a plan view of the structure 50 shown in Figure 3.

Figure 5 is a plan view of a washer disclosing certain features of the invention.

Figure 6 is a sectional view of a driving wheel embodying certain features of the

invention, said section being taken approximately on line 6—6 of Figure 3. 55

Figure 7 is a fragmentary sectional view through Figure 2 on line 7—7.

Figure 8 is an interior elevation of part 60 of the supporting box shown in Figure 3.

Figure 9 is a sectional view through Figure 8 on line 9—9.

Figure 10 is a top plan view of the structure shown in Figure 8.

Figure 11 is an inside elevation of the 65 second half of the box shown in Figure 3.

Figure 12 is a sectional view through Figure 11 on line 12—12.

Figure 13 is a top plan view of the structure 70 shown in Figure 11.

Figure 14 is a front view of the bar and associated parts shown in Figure 1.

Figure 15 is an enlarged fragmentary sectional view showing a single boiler tube 75 with a baffling structure arranged therein, said baffling structure embodying certain features of the invention.

Figure 16 is a sectional view through Figure 15 approximately on line 16—16.

Figure 17 is a view similar to Figure 15 80 but showing the parts in an operated or spiral position.

Figure 18 is an enlarged fragmentary view showing more in detail the particular 85 structure of the spiral sections.

Figure 19 is a sectional view through Figure 18 on line 19—19.

Figure 20 is a perspective view of the 90 spiral member shown in Figure 18.

Figure 21 is a detail perspective view 95 similar to that shown in Figure 20 but showing a modified form of shoulder.

Figure 22 is a view similar to Figure 2 but showing a modified form of the invention 95 wherein the device is adapted to be used for heating water or superheating steam.

Referring to the accompanying drawings by numeral, 1 indicates a furnace of any desired type and 2 a tubular boiler provided with any desired number of heating tubes 100. There is a space 4 arranged at the rear of the boiler 2 and a chamber 5 arranged in the front part of the boiler, said chamber being usually found in boilers of this type. The chamber 5 is utilized in accommodating certain pipes, gearings and other parts embodying certain features of the in- 105

vention whereby the sides or shape of the boiler need not be varied and in fact by reason of the usual chamber 5 in boilers now in common use, inventions may be easily applied to boilers already manufactured.

When using the invention shown in Figure 1, means are provided for retarding the passage of burning gas so that the water in the boiler will absorb a maximum number 10 of heat units and in addition means are presented which may be used to inject steam into the tubes at different points for increasing the combustion in the tubes and also for increasing the draught. As shown in this 15 figure, the tubes 3 are provided with a baffling structure 6 consisting of a number of independent spiral sections 7 mounted on a suitable tube 8 and freely rotatable thereon. If desired, the tube 8 may be one continuous 20 tube for supporting the section 7 but preferably it is formed in a number of parts connected by tubular connectors 9, each of said connectors having one or more inclined apertures 10 whereby steam forced into the 25 tubes will be discharged at a number of points in the boiler tube 3. Arranged at one end of each of the tubes 8 is a gear wheel 11 having a plurality of gears or projections 12 designed to straddle the web of the 30 end spiral section 7 as shown in Figure 15 whereby when the gear wheel 11 is rotated, the section 7 will be moved into a spiral formation or into an aligned formation according to the direction of movement of the gear 35 wheel.

From Figures 15 to 19, it will be observed that the baffling member 6 is formed from a large number of spiral sections 7 constructed as shown in Figure 20. Each section 40 is formed with a tubular body 13 adapted to fit over the tube 8 and with a pair of semi-tubular portions 14 and 15, said semi-tubular portions being less than a half tube and arranged to project beyond the 45 tubular portion 13 at each end so as to overlap the ends adjacent the tubular portion 13. By reason of the fact that the portions 14 and 15 are less than a half tube, there is provided a loose motion in a circle so that 50 when the sections 7 are rotated in one direction, the respective portions 14 and 15 will strike the webs 16 and 17 of the next adjacent sections 7 and cause an alignment of the respective sections as shown in Figure 55 16. If rotated in the opposite direction, these same portions 14 and 15 will engage on their opposite edges the webs 16 and 17 and cause a spiral formation as shown in Figure 17. On some occasions it may be desirable to 60 have certain of the sections formed in spiral relation as shown in Figure 17 while others are arranged in alignment as shown in Figure 16. In order to accomplish this result, the respective gear wheels 11 are rotated 65 for one or more revolutions and the result

will cause the device to appear as shown in Figure 1. It will be noted that the gear 11 and associated parts are at the forward end of the boiler so that when moving the parts to a spiral position, the end of the baffling members toward the front of the boiler will be first formed into a spiral.

When the parts are as illustrated in Figure 1, the flame may freely pass through the rear part of the tube 3 but is checked at 70 the front part for permitting the water in the boiler to absorb heat units therefrom. The rear ends of the baffling members are connected with suitable plates 18 as shown in Figure 2 so as to be held against rotation whereby the various spiral sections 7 may be freely moved until all are arranged in spiral relation or until all are arranged in alignment. The plates 18 may form any 75 suitable or desirable framework to properly act as a fixed holding member. At the front a more elaborate arrangement is provided which consists of a number of metal frames 19, each frame 19 being provided with sections 20 and 21, said sections interlocking for forming a housing for receiving the respective gears 11. It will also be noted that the section 20 is provided with a journal box 22 which supports the tube 8. Each of the sections 21 is provided with a 80 chamfered corner 23 and a lug 24 at the corner. If desired, a similar structure may be provided in section 20 so as to accommodate the respective washers 25 and suitable bolts 26 whereby the various frames 19 are 85 secured together in a nested formation as shown in Figure 7. When nested in this manner the boxes 22 are in a line with the center of tubes 3 so as to properly support 90 said tubes and permit a free rotation of the spiral member 7 arranged loosely thereon. It will be noted that by this construction a built-up spiral or framework is produced 95 which encloses the respective gear wheels 11 but permits any one gear wheel to be removed at any time together with its operation 100 of spiral member 7 and other parts without disturbing the remaining gear 105 wheels or other members. All of the frames 110 19 are of the same size except those at the periphery which are bolted by the bolts 26 to the flange 27. These frames are merely cut off sufficiently to produce a proper fit while the remaining frames are of the same 115 size and shape and all of the gear wheels 11 are also of the same size and intermesh. This 120 will naturally cause a reverse rotation of certain of the gears in respect to the plates. It will, of course, be necessary to make the 125 adjacent spiral members 7 operate in reverse directions so that all of the spiral members may be thrown into a spiral or removed from a spiral simultaneously. As 130 all of the gears 11 are in mesh, they may be driven by a single power gear 28 secured

to a stub shaft 29 carrying a bevel gear 30. This bevel gear is supported by a suitable bracket 31 bolted or otherwise secured to one of the frames 19 and the bevel gear 30 meshes with a driving gear 32 secured to shaft 33. This shaft extends outwardly through a box 34 and is provided with a hand wheel 35 whereby the various gears 11, spiral members 7 and associated members may be properly actuated at any time. A notched wheel 36 is rigidly secured to the shaft 33 and co-acts with a manually actuated and pivotally mounted catch bar 37, pivotally connected with the box 34.

When it is desired to rotate the shaft 33, the catch bar 37 is raised and the shaft rotated to the desired extent. The lever 37 is then moved downwardly into one of the notches of member 36 and thereby locks all of the parts against accidental movement. In order to permit the operator to know the exact condition of the respective spiral members 7, a dial 38 is provided on box 34 over which the pointer 39 moves. The dial is calibrated to show the exact position of the spiral members 7 according to the position of the pointer 39. The pointer 39 is rigidly secured to a shaft 40, which shaft is keyed or otherwise secured to a gear wheel 41 meshing with a pinion 42 loosely mounted on the shaft 33 but rigidly secured to a gear wheel 43 meshing with a pinion 44 loosely mounted on shaft 40. The pinion 44 is rigidly secured to a gear wheel 45 meshing with a pinion 46, said pinion 46 being keyed or otherwise rigidly connected with shaft 33. In this way a reducing train of gears is provided which will cause the pointer 39 to move in proportion to the movement of the spiral members 7.

In Figures 1, 2 and 14 will be seen, what may be termed, an ejecting mechanism for steam co-acting with the spiral member 7 and the tube 8. A mixture of a certain quantity of steam with the gases in the tube 3 has been found to be beneficial in respect to producing a better chemical union and, consequently, a better combustion of the gases. In addition, the use of jets of steam in the tubes 3 will increase the draught. In forming a structure for carrying out these purposes, the tubes 8 are utilized not only as a support for the spiral section 7 but has a passage-way for the steam. These tubes are divided into sections by connecting sleeves 9, each sleeve having a series of apertures 10 extending in such a direction that the jet of steam will be discharged toward the discharge end of the respective tubes 3. In the tubes 8, a stationary block 47 may be provided as shown in Figure 2 or a sliding block 48. If desired, both of these dividing members may be used in the same boiler at the same time. These dividing members are provided so that steam may be admitted at either end or at both ends and even distributed to the openings 10. A distributing box 49 is connected with each tube 8 at each end and a header 50 connected to each series of boxes 49. The respective headers are connected to a suitable single source of steam supply. In each of the boxes 49 a pointed member 51 is provided with the point at the end of tube 8 or extending a short distance therein whereby steam is permitted to freely enter the tube but the dividing block 48 cannot leave the tube. Preferably, steam is turned on both ends of the tube simultaneously and, consequently, there will be an even pressure against the block 47 and an even distribution of the steam through the various apertures 10 of the various sleeves 9. In case the sliding block 48 is used the pressure of the steam in the respective boxes 49 at each end is the same and, consequently, the block 48 will automatically position itself in the center and allow the same to be distributed as if it were fixed. Where the stationary block 47 is used, steam must be admitted at both ends in order to use all of the sleeves 9 whereas if the sliding block 48 is used, steam may be admitted at both ends or at either end. When admitted at one end, block 48 is forced to the opposite end and steam is thereby permitted to easily pass out the apertures 10 in all of the sleeves 9. It is, of course, evident that suitable valves may be provided as shown in Figure 14 or other means of control may be provided for the steam. In addition to the use of steam for the purpose specified or for any other purpose, air may be used which is usually more effective in cleaning out soot from the tubes than steam. If desired, steam can be turned off from the pipes 50 and air turned on whenever it is desired to clean the tubes from soot and after the cleaning operation, if steam is desired, the air could be turned off and steam admitted, though the use of a certain quantity of air in the tubes will produce desirable results with certain kinds of fuel. It is, therefore, evident that either steam or air may be freely used for either cleaning or assisting the combustion or assisting the draught.

In Figure 21 will be seen a slight modified form of spiral member wherein the shoulders 14' and 14'' extend from the same end of the tubular body. Referring to Figure 22, it will be seen that the tubular connecting members 9' are solid instead of perforated as in the preferred form. In this form of the invention a pipe 52 is connected to a suitable source of steam supply and the steam is allowed to pass into the tube 8' and from thence through the opposite header and out the discharge pipe 53 where it may be used as superheated steam. If desired, this arrange-

ment could be provided for any or all of the flues though ordinarily it is used only with the upper flues. This will permit the tubes 8' in the lower flues to be used as water heaters. When used as water heaters the water is passed in through the pipe 54 to the header at one end of the boiler and from thence through the lower tube 8' to the header at the opposite end and from thence 10 out the discharge pipe 55 to any suitable point. As the bottom of the boiler is cooler than the upper part, the tubes in the lower flues are preferably used for heating water while the upper tubes are preferably used 15 for superheating steam though if desired all of the tubes could be utilized for either purpose by a proper connection of the tubes.

What I claim is:

1. In a device of the character described, 20 the combination with a boiler having flues, of means for retarding the passage of the flame and the products of combustion through said flues, said means comprising a central supporting member extending longitudinally through each of said flues, a plurality of sleeves rotatably mounted on said supporting member and provided with spiral formed webs, each of said sleeves having an overhanging section for transmitting rotary motion to the next adjacent section, and means for rotating the end sleeve in each of the flues:
2. In a device of the character described, 35 the combination with a boiler having a flue therein, of a supporting tube extending longitudinally through said flue, a plurality of baffling members having spiral webs rotatably mounted on said tube, each of said baffling members having overhanging shoulders adapted to cause the webs of the baffling members to form into alignment when rotated in one direction and to form into a spiral when rotated in the opposite direction, said tube being provided with a plurality 40 of openings intermediate its ends, and means for supplying steam under pressure to said tube whereby jets of steam will be discharged into said flue from said openings.
3. In a device of the character described, 45 the combination with a boiler having a flue, of adjustable baffling means arranged in said flue, means for adjusting said baffling means to retard to a greater or less extent the passage of flame and articles of combustion through the flue, a tube extending through said flue having a number of openings, and means for supplying steam under pressure to said tube, said means including 50 a box for distributing the steam to the tube and a supply header for maintaining the pressure of steam in said box.
4. In a device of the character described, 55 the combination with a boiler having a plurality of flues therein, of baffling members

arranged in said flues, said baffling members being adjustable to retard to a greater or less extent the passage of flame or products of combustion through the flues, a gear wheel secured to each of said baffling members for adjusting the same, the gear wheels associated with the baffling members in each flue meshing, a supporting frame for said gear wheels, a driving mechanism connected with said gear wheels for simultaneously rotating the same, and an indicating mechanism connected with said driving means for automatically indicating the position of the baffling means.

5. In a device of the character described, 70 the combination with a boiler having a plurality of flues, of baffling means arranged in each of said flues, means for varying the baffling action thereof, a tube in each flue for supporting the baffling means, said tubes having a plurality of apertures, a division block arranged in said tubes, and means for supplying steam to both ends of the various tubes.

6. In a device of the character described, 75 the combination with a boiler having a plurality of flues, a baffling structure arranged in each of the flues, means for adjusting the various baffling structures for causing a variation in the baffling action, a tube extending through each of said flues, said tubes being provided with apertures extending substantially in line with the line of draught, a slideable block arranged in each of said tubes, and means at each end of said tubes for supplying steam under pressure thereto whereby when steam is supplied from both ends the sliding block will remain substantially centrally in the tube and when supplied to one end will move to one end of the tube for permitting steam to escape out of all of said apertures.

7. In a device of the character described, 100 the combination with a boiler provided with a plurality of flues, a baffling structure arranged in each flue, means for shifting the position of said baffling structure for increasing and decreasing the baffling action thereof, a supporting member extending through each flue for supporting the baffling structure therein, and a supporting framework for said supporting means, said supporting framework being provided with a plurality of frames and bolts for connecting the frames together, each of said frames being formed into a pair of sections having interlocking parts positioned to make a solid frame when said bolts are in position.

8. In a device of the character described, 105 the combination with a boiler having flues, of baffling members arranged in said flues formed with spiral baffling sections, and tubular supports, and means for directing fluid into any of said tubular supports.

PETER O. ROTH.
